AIR VENTILATING DEVICE

Kurt J. Dosmar, New York, N. Y.

Application September 27, 1946, Serial No. 699,860

5 Claims. (Cl. 98—36)

1

This invention relates to air cooling or ventilating systems and apparatus for rooms of homes.

It is an object of the present invention to provide an air cooling or ventilating system in which the air will be directed in the direction desired in the form of curtain like air streams, whereby a more favorable control and effect of the ventilating air can be had.

It is another object of the invention to provide an air ventilating apparatus which can be adapted or located in a position surrounding the person whereby a full effect of the air can be had without greatly affecting any of the other people who may be in the same room.

It is another object of the invention to provide an air ventilating apparatus in which the air is blown in a curtain like manner, whereby to provide an even flow about the person or within a window opening to control the air entering the same and thus not be directed in full blast upon the body of a person within the room.

According to the invention, a wind motor in the form of a box containing an electric motor and fans driven therefrom has a plurality of outlets to which a flexible air hose can be connected to deliver air to any one or a plurality of nozzle devices adapted to be located upon the floor about the person to be benefitted by the air streams or within a window opening as upon the sill thereof.

The motor of the wind box is connected by an electric cord with any appropriate outlet within a room. If the person to be benefitted is to sit in a chair the several nozzle devices will be disposed on the floor about the chair, at opposite sides thereof and at the front and rear. Vertical curtains of air will be extended upwardly to enclose the person therewithin. The blown air will not be directed upon the person's body but will be extended up vertically above the same thereby causing a removal of the air within the region of the person without the person being struck by a direct blast of the air. When the various outlets of the wind box are not in use they may be covered with a closure cap or plug.

Another arrangement of the present invention is where one of the nozzle devices is located on a sill of an open window. Outside air tending to enter the room will be stabilized by the vertical curtain of air being forced upwardly from the sill. Such air that is entering the room therefore will be directed vertically upwardly and not directly upon a person within the room.

For further comprehension of the invention,

2

and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of the arrangement 10 wherein the wind box is connected to a single nozzle device resting upon a sill of a window to direct a curtain of air upwardly and normal to the axis of the window opening.

Fig. 2 is a cross sectional view of the wind box 15 and a partial cross sectional view of the nozzle device adapted for use in a window opening.

Fig. 3 is an illustrative view of the arrangement set up for use above a chair in which a person may be seated and employing a plurality of nozzle devices.

Fig. 4 is a perspective view of a modified form 20 of a nozzle device adapted to rest upon a flat horizontal surface wherein the air curtain may be directed either to a vertical or to a position angled therefrom.

Fig. 5 is a transverse cross sectional view taken along the line 5—5 of Fig. 4, looking in the direction of the arrows thereof.

Fig. 6 is a perspective view of a modified form 30 of air curtain forming device wherein the air flow can be controlled.

Referring now to the figures, 10 represents a wind box or breeze creating machine having a plurality of outlets 11 in the top thereof to each 35 of which a flexible hose 12 may be connected. When the outlets 11 are not in use they may be closed by a threaded stopper or plug 13. The hose 12 leads to a nozzle device 14 which may be located at any place on the floor or in the sill of 40 a window opening. In the illustration of Figs. 1 and 2, the nozzle device 14 is shown disposed in the sill of an opening 15 of a window.

The wind-box 10 has in its interior an electric motor 16 which is connected to fan blades 17 and 45 18 on opposite sides thereof through appropriate respective gear connections 19 and 21. By the blades 17 and 18 air is drawn into the box 15 through appropriate inlet openings 22 and is directed toward the outlets 11 in the top of the box. The outlet having the hose 12 connected thereto will receive the air and this air will be directed through the hose to the nozzle or curtain-forming device 14. The motor 16 is of the electric type and receives its power or current for 50 the operation of the same through a cord 23

adapted to be connected through its plugs 24 to a receptacle in the room. The box 10 can be located anywhere in the room and the motor 16 can be set in operation by pushing a switch button 25 located on one side of the box.

The nozzle device 14 is preferably made of rubber or aluminum and is of elongated shape having a plurality of holes 26 or perforations arranged in a longitudinally extending row and slightly spaced from one another so as to throw upwardly a vertical curtain of air. This vertical curtain of air is indicated at 27 and is shown to cover the full area of the opening 15. This vertical curtain of air will tend to break up any wind or air that is tending to naturally pass into the window opening and prevent it from flowing upon a person within the room. This air tending to enter the window opening will be blown upwardly and into the top part of the room by this air curtain 27, and thereby directed to the room at a point where it could not fall or strike upon one in the room. At the top of the window opening there may be provided a reflector 28 by which the air may be reflected into the interior of the room. This reflector 28 may be coupled as indicated at 29 upon the exterior of a top window 30 or it may be connected to the interior with appropriate fittings being provided upon the inner window which is up so that the reflector will be inside during dry days. On wet or rainy days reflector 28 is located on the exterior as shown, whereby to keep out too much moisture from the room.

Referring now particularly to Fig. 3, there is shown an arrangement where an air curtain is placed about a person sitting in a chair 31. In this instance, the box 10 may have more than the four outlets shown in Fig. 1 and each of these outlets are connected to a nozzle curtain forming device 32. There are a plurality of these devices 32 strategically positioned about the chair, one large arcuate shaped one 32' being at the rear of the chair, one being located at each side of the chair and two located in front of the chair. It will be apparent that when the wind creating box 10 is turned on that there will be a plurality of air curtains extended upwardly alongside of the person sitting in the chair 31 and surrounding him. None of the air will be directed against his body and thus he will not feel any uncomfortable effect from the system. Air will be gradually removed from the zone of his presence and replenished by new air. No air will be blown directly on the body of the person as would be the case of an ordinary electric fan as when it is used to cool a person.

Referring now particularly to Figs. 4 and 5, there is shown a modified form of nozzle or air curtain forming device. This device has the usual elongated member but this member is of circular section, as indicated at 35, so that it may be rotated upon a support 36 and in a top groove thereof in which the member can be rested.

The member 35 has the hose 12 connected to it and also has a plurality of longitudinally spaced air holes 37. Normally, the air would be directed straight upwardly as indicated by the arrow 38 of Fig. 5, but should it be desired to have the air curtain angled from the vertical the member 35 can be rotated in its support 36 from one side to the other so that its air curtain will be directed as indicated by either of the arrows 39 or 41 depending upon which way the member 35 has been turned. The air would then be directed still in the form of a curtain and need not be turned to such an extent where it would directly contact the person to be benefitted by this sys-

tem. The device shown in Figs. 4 and 5 may thus be substituted for the device 14, where the occasion demands that an adjustable device be used.

Referring to Fig. 6, a base 41 has an upwardly extending portion 42. A hollow cylinder 43 is provided with a pair of spaced rows 44 and 45 of air holes. If desired the cylinder can be rotated under the portion 42 to block off the row 45 to cut down the air capacity to one-half.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a portable air ventilating apparatus having a source of air under pressure, an air curtain forming device rested on a window sill and connected to the source of air under pressure, said forming device being provided with a plurality of longitudinally spaced air outlets for directing a curtain of air upward across the open window so as to diffuse currents of air which would normally pass through the window opening at right angles to the curtain of air, a reflector disposed on the side of the window opening opposite the air curtain forming device and normally projected into the room for directing the curtain of air into the room after traversing the window opening, and means releasably attaching the reflector to the outside of the window during inclement weather to prevent rain from entering the open window.

2. In a portable air ventilating apparatus having a source of air under pressure, an air curtain forming device rested on a window sill and connected to the source of air under pressure, said forming device being provided with a plurality of longitudinally spaced air outlets for directing a curtain of air upward across the open window so as to diffuse currents of air which would normally pass through the window opening at right angles to the curtain of air, a reflector disposed on the side of the window opening opposite the air curtain forming device and normally projected into the room for directing the curtain of air into the room after traversing the window opening, and means releasably attaching the reflector to the outside of the window during inclement weather to prevent rain from entering the open window, said air curtain forming device comprises a tubular member formed with the row of air outlets along the top side, and means supporting the tubular member so that it may be turned slightly to vary the discharge angle of the curtain of air.

3. In a portable air ventilating apparatus having a source of air under pressure, an air curtain forming device rested on a window sill and connected to the source of air under pressure, said forming device being provided with a plurality of longitudinally spaced air outlets for directing a curtain of air upward across the open window so as to diffuse currents of air which would normally pass through the window opening at right angles to the curtain of air, a reflector disposed on the side of the window opening opposite the air curtain forming device and normally projected into the room for directing the curtain of air into the room after traversing the window opening, and means releasably attaching the reflector to the outside of the window during in-

lement weather to prevent rain from entering the open window, said air curtain forming device comprises a tubular member formed with the row of air outlets along the top side, and means supporting the tubular member so that it may be turned slightly to vary the discharge angle of the curtain of air, said supporting means comprising a base formed with a longitudinal groove in which the tubular member is rested to be manually turned as desired.

4. In a portable air ventilating apparatus having a source of air under pressure, an air curtain forming device rested on a window sill and connected to the source of air under pressure, said forming device being provided with a plurality of longitudinally spaced air outlets for directing a curtain of air upward across the open window so as to diffuse currents of air which would normally pass through the window opening at right angles to the curtain of air, a reflector disposed on the side of the window opening opposite the air curtain forming device and normally projected into the room for directing the curtain of air into the room after traversing the window opening, and means releasably attaching the reflector to the outside of the window during inclement weather to prevent rain from entering the open window, said forming device comprising a tubular member formed with a plurality of rows of air outlets through which air may discharge, and means supporting the tubular member so that certain of the rows of outlets may be blocked to control the volume of discharging air.

5. In a portable air ventilating apparatus having a source of air under pressure, an air curtain forming device rested on a window sill and connected to the source of air under pressure, said forming device being provided with a plurality of longitudinally spaced air outlets for directing a curtain of air upward across the open window so as to diffuse currents of air which would normally pass through the window opening at right angles to the curtain of air, a reflector disposed

on the side of the window opening opposite the air curtain forming device and normally projected into the room for directing the curtain of air into the room after traversing the window opening, and means releasably attaching the reflector to the outside of the window during inclement weather to prevent rain from entering the open window, said forming device comprising a tubular member formed with a plurality of rows of air outlets through which air may discharge, and means supporting the tubular member so that certain of the rows of outlets may be blocked to control the volume of discharging air, said supporting means comprising a base member formed with a longitudinal groove in which the tubular member is rotatively rested, said base member having a portion at one side extending upwardly at a point adjacent one of the rows of outlets so that the tubular member may be rotated to a position in which the upstanding portion will block the discharge of air from one row of openings.
